US0D1078081S

(12) **United States Design Patent** (10) **Patent No.:** **US D1,078,081 S**
(45) **Date of Patent:** **** Jun. 3, 2025**

(54) **SPECIMEN COLLECTOR HAVING A DETACHABLE CAPTURE VESSEL**

(71) Applicant: **Phuong Nguyen**, San Diego, CA (US)

(72) Inventor: **Phuong Nguyen**, San Diego, CA (US)

(**) Term: **15 Years**

(21) Appl. No.: **29/852,628**

(22) Filed: **Sep. 8, 2022**

(51) **LOC (15) Cl.** **24-02**

(52) **U.S. Cl.**

USPC **D24/216**

(58) **Field of Classification Search**

USPC D24/107, 186, 216, 232, 233, 234, 121, D24/122, 223, 224, 225, 227, 231; D10/81

(57) **CLAIM**

The ornamental design for a specimen collector having a detachable capture vessel as shown and described.

DESCRIPTION

FIG. 1 is a front, top, and left side perspective view of a specimen collector having a detachable capture vessel showing my new design.

FIG. 2 is a back, bottom and right side perspective view thereof.

FIG. 3 is a top view thereof.

FIG. 4 is a bottom view thereof.

FIG. 5 is a left side view thereof, the right side being a mirror image thereof.

FIG. 6 is a front view thereof; and,

FIG. 7 is a back view thereof.

1 Claim, 3 Drawing Sheets
